Patented Feb. 20, 1923.

1,446,329

UNITED STATES PATENT OFFICE.

ARTHUR E. BENEDICT, OF SOUTH NORWALK, CONNECTICUT.

FLUSH VALVE.

Application filed March 18, 1922. Serial No. 544,780.

To all whom it may concern:

Be it known that I, ARTHUR E. BENEDICT, a citizen of the United States, residing at South Norwalk, county of Fairfield, State 5 of Connecticut, have invented an Improvement in Flush Valves, of which the following is a specification.

This invention relates to outlet valves for liquid tanks generally although it is more 10 especially designed for use in flush tanks for water closet basins.

It is an object of the invention to provide a simple and durable valve and outlet mechanism for flush tanks which will be reliable 15 and positive in operation.

It is a further object of the invention to provide a valve and valve mechanism of this type which will have means for retaining the valve in its open position until the tank 20 has become emptied and will then insure the closing of the valve.

It is a still further object of the invention to provide an improved, simple, and easily 25 manufactured valve for this type of mechanism which will last indefinitely.

With these and other objects in view, I have devised the constructions illustrated in the accompanying drawing, in which

Fig. 1 is a sectional view through one form 30 of my device.

Fig. 2 is a similar view through a slight modification, and

Fig. 3 is a transverse section through the valve.

Reference numeral 5 indicates a water tank, especially a flush tank for water closet basins, which is usually lined with sheet metal indicated at 6. Extending through 7 the bottom thereof is the outlet fixture 7 mounted in any suitable manner, preferably 40 having a flange 8 resting on suitable packing 9 and clamped in position by means of a nut 10. The connection from the outlet to the basin is not shown. This outlet is provided 45 with the usual horizontally extending valve seat 11 upon which the valve 12 is adapted to seat. Extending laterally from the outlet, below its seat, is a tubular connection 13 which tubular connection extends upwardly 50 within the tank to a point above the liquid level therein when the tank is filled and then downwardly to a position adjacent the level of the valve seat 11, and communicates with the tank at this level. This level is prefer- 55 ably slightly above the top surface of the

outlet. I have disclosed, in Figures 1 and 2, two slightly different constructions of this upwardly and downwardly extending connection. In Fig. 1, I have employed two concentric tubes 14 and 15, the inner tube 60 being connected at its lower end to the connection 13 from the outlet and open at its upper end within the outer tube which is closed at its upper end and open at its lower end 14' at a level slightly above the outlet. 65 The outer tube is spaced from the inner tube by any suitable means such as set screws 16 at its lower end and horizontally extending pins 17 at its upper end.

Located above the outlet, is a supporting 70 member 18, preferably dome shaped or inverted cup shaped, and provided with a seat 19 opposed to the seat 11 and in which the upper surface of the valve 12 is adapted to seat. A tubular connection 20 leads from 75 this support, above its seat, to the outer tube 15 between the ends thereof as indicated at 32.

In the form shown in Fig. 2, instead of having the tubes concentric, I have placed 80 them laterally of each other, the two sections being indicated at 21 and 22, the section 21 being connected to the lateral connection 13 the same as tube 14 in Fig. 1 while the tube 22 is connected to the tube 21 at its upper 85 end, as shown at 23, extends downwardly and opens to the tank at point 24 slightly above the top of the outlet, the same as outer tube 15 in the form shown in Fig. 1. The tubular connection 20 from the support- 90 member 18 is connected to the tube 22 between its upper and lower ends as shown at 23 the same as it is connected to the outer tube 15 in the form shown in Fig. 1. Both forms have the usual water supply pipe 25 and 26, discharging into the tube 14 in Fig. 1, and 21 in Fig. 2, to fill the trap in the usual manner after the basin has been flushed.

My improved valve 12 is preferably com- 100 posed of light sheet metal, such as aluminum, and comprises a substantially dome shaped member, as illustrated, open at its lower end, as shown at 27, the diameter of this opening being less than the greatest 105 diameter of the valve so that the sides there- of extend inwardly, as shown at 28, below this greatest diameter. Connected to the top of the valve, by any suitable means, is a lifting rod 29 extending through a suitable 110

guide 30 and may be connected at its upper end to the usual operating mechanism, a connection from which is indicated at 31.

The operation is as follows:

5 The two different modifications shown operate exactly the same and the tank is filled with water to the level substantially as shown, this level being about at the level of the connection of tube 14 with tube 15, and
10 from tube 21 to tube 22. Upon lifting of the valve 12 from its seat, as it is filled with air, it will rise and seat in the seat 19 of supporting member 18, the buoyancy of the water raising it to this position if it is not
15 lifted thereto by the operator. As the water flows out the outlet, the syphonic action of the column of water therein creates a suction in the pipes 14, 15 and 20 in the form shown in Fig. 1 and in pipes 21, 22 and 20 in
20 the form shown in Fig. 2, and causes water to flow in at the lower open ends of the pipes 15 and 22, past the connections 32 and 33 to these pipes of tube 20 from the supporting member 18, thus creating a partial vacuum
25 in this member above the valve and supporting the same against the valve seat 19 until the level of the water in the tank reaches the lower ends of the pipes 15 and 22, when air enters the tubes breaking the suction or par-
30 tial vacuum above the valve allowing it to drop to the lower valve seat 11. It will be apparent from this that there is positive means for holding the valve elevated until the tank has been emptied or the liquid there-
35 in has reached a certain definite level, when the valve is automatically released and may move to closed position. The improved valve construction is much more durable than the old type of rubber ball besides being much
40 lighter which is of special advantage in use with the specific suction holding means described, besides being simpler in construction than the rubber ball, and being easier and cheaper to manufacture.

45 Having thus described the nature of my invention, what I claim is:

1. A device of the character described comprising an outlet, a valve for closing the entrance to said outlet, an inverted cupped member spaced above said outlet and adapted to receive said valve, an upwardly extending tube communicating with said outlet below the valve, a tube leading from the upper portion of said pipe downwardly to a level a short distance above the level of the entrance to the outlet and open at its lower end, and a tube leading from the cupped member to and communicating with the latter tube intermediate its ends.

60 2. An outlet valve mechanism for liquid tanks comprising an outlet having a valve seat, a valve for said seat, a lateral branch

connected with said outlet below the said seat and extending upwardly in the tank and then downwardly and in open communication with the tank below the normal liquid level therein, an inverted cupped member above the valve in which the valve is adapted to seat, a tubular connection from said cup to said lateral branch above its open 70 lower end, and means for lifting the valve from its seat.

3. An outlet valve mechanism for liquid tanks comprising an outlet having a valve seat, a valve for said seat, means for lifting 75 the valve from its seat, a supporting member above said valve provided with a seat for the upper portion thereof, a connection from the outlet below its seat to the support above its seat whereby a partial vacuum is produced in said support by the suction produced by the syphonic action of the liquid flowing through said outlet, and means in the tank for breaking the syphonic action after the tank is discharged.

85 4. An outlet valve mechanism for liquid tanks comprising an outlet having a valve seat, a valve for said seat, means for lifting the valve from its seat, a supporting member above said valve provided with a seat for the upper portion thereof, a connection from the outlet below its seat to the support above its seat whereby a partial vacuum is produced in said support by the suction produced by the syphonic action of the liquid flowing through said outlet, and a connection 90 from the tank below the normal liquid level therein to said first connection.

5. An outlet valve mechanism for liquid tanks comprising an outlet having a valve seat, a valve for said seat, a supporting member above said valve provided with a seat for the upper portion thereof, a tubular connection from the outlet below its seat to said supporting member above its seat, a connection 100 from the said tubular connection to the tank at a level adjacent the level of the entrance to said outlet, and means for raising the valve from its seat.

105 6. An outlet valve mechanism for liquid tanks comprising an outlet having a valve seat, a valve for said seat, a supporting member above said valve provided with a seat for the upper portion thereof, a tubular connection from the outlet below its seat extending upwardly in the tank and then downwardly and having communication with the tank at a level adjacent the level of the inlet to the outlet, a tubular connection from the support to the latter connection below the 115 top thereof, and means for lifting the valve from its seat.

In testimony whereof I affix my signature.
ARTHUR E. BENEDICT.
